UNITED STATES PATENT OFFICE

IRVING R. HIPPENMAYER, OF WAUKESHA, WISCONSIN, ASSIGNOR TO THE CREAMERY PACKAGE MFG. COMPANY, OF CHICAGO, ILLINOIS, A CORPORATION OF ILLINOIS

BOTTLE-WASHING MACHINE

Application filed November 15, 1928. Serial No. 319,485.

The invention relates to bottle washing machines of the type wherein bottles are moved through successive treatment zones by means of an endless conveyor having bottle carrying pockets.

In such machines, the conveyor commonly comprises chain or link belts supporting cross rows of bottle pockets. Use causes wear in the link connections with resulting elongation or slack in the belts. To compensate for the slack thus developed, it is common to provide adjustable bearing supports for certain of the sprockets upon which the conveyor belts are supported, which may be shifted in position to take up the slack in the belts.

The bottle pockets are constructed with open receiving ends, and, in the operation of the washing machine, the bottles protrude partially from the pockets. In those portions of the path of the conveyor where the open ends of the pockets are upward, the bottles are retained therein by gravity. In other portions of the conveyor path where the open ends are downward or downwardly inclined, and where the pockets swing about on the comparatively short radius of the conveyor supporting sprockets, it is necessary to provide retaining rails parallel to or concentric with the path of the pockets, with which the protruding ends of the bottles are in sliding abutment for their retention in the pockets. It is obvious that a shifting of the supporting sprockets, in taking up slack in the conveyor belts, also shifts the adjacent portions of the operating path of the conveyor, and upsets its parallel or concentric relation to the bottle retaining rails, whereby the latter do not function properly.

It is the object of the present invention to provide a retaining rail structure and support which is automatically adjustable, with the shifting of position of the supporting sprockets and conveyor path in a bottle washing machine of the type described, to maintain the retaining rails in parallel or concentric equi-distant relation to the operative path of the conveyor at all times. Other objects and advantages will be apparent in the following description of a preferred embodiment of the invention illustrated in the accompanying drawings.

Referring to the drawings, Fig. 1 is a side view in elevation of a portion of a bottle carrying conveyor with supporting sprockets, 55 and retaining rails associated therewith embodying the features of the invention. Fig. 2 is a detailed side view of a means for shifting the position of certain of the supporting sprockets for removing slack from the conveyor. Fig. 3 is a fragmentary cross sectional view taken on the plane of the line 3—3 in Fig. 1. Fig. 4 is a rear view in elevation of the structure shown in Fig. 1, with the conveyor removed. Fig. 5 is a detailed side 60 view of a retaining rail in its relation to the sprockets. Fig. 6 is a structural detail of the rail support. Fig. 7 illustrates a modified form of retaining rail.

In the drawings, the reference numeral 1 indicates the front one of a pair of similar sprockets mounted in spaced relation upon a shaft 2 supported in suitable bearings, of which one is indicated at 3, provided upon opposite side walls, of which one is shown 75 at 4, within a bottle washing machine. Another pair of spaced sprockets 5, positioned upwardly of the sprockets 1, are mounted on a shaft 6 supported in bearings also mounted in the side walls of the machine. The latter 80 bearings, illustrated in Figs. 2 and 4, are adjustable in position, and each comprises a sliding block 7 in which the shaft 6 is journaled, the block 7 being supported upon the outer side of the wall 4, and the latter 85 having a slot 8 through which the shaft extends. The block 7 is supported for sliding movement between a pair of spaced retaining brackets 9 secured to the wall 4, and across the ends of which is a connecting bracket 10 90 carrying a screw 11 positioned axially of the slideway between the brackets 9 and endwardly abutting the slideway bearing block 7. The position of the block 7 is adjustably determined by the abutment with the screw 95 11, the latter being secured in adjusted position by a lock nut 12.

A pair of spaced parallel chain belts are operatively supported in part upon the pair of sprockets 1 and 5, the near one of the pair 100

of belts being indicated at 13. Spaced rows of bottle pockets 14 are carried by and between the belts 13, the pockets being suitably mounted upon a cross bar 15 (Fig. 3) end-wardly secured to the respective belts 13. The described adjustable mounting of the bearings for the shaft 6 permits the adjustable increase of the distance between centers of the sprockets 5 and 1, thereby taking up whatever slack may develop in the chains 13 and maintaining the proper relation of movement of the pockets 14 to the several cleansing devices commonly provided in such machines.

As illustrated in Figs. 1 and 3, the bottle pockets passing with that portion of the conveyor run between the sprockets 1 and 5 are angularly inverted so that bottles positioned in the pockets would fall therefrom if retaining means were not provided. To retain the bottles in the pockets, relatively stationary rails 16 are provided, the rails being supported in adjacent parallel relation to the path of movement of the open ends of the serially arranged bottle pockets, so that bottles positioned in the pockets, as indicated at 17 in Fig. 3, rest upon and slide over the rails 16 while the pockets are in inverted position.

The rails 16 are pivotally supported at their lower ends upon a stationary cross bar 18 supported at its ends upon the side walls of the machine, each end of the bar preferably resting in a laterally open pocket formed in a bracket 19 secured to the respective side walls, the bar being removably retained against lateral displacement from the respective pockets by means of a pin 20 positioned in each bracket across the lateral opening from the pocket (see Fig. 6). Each rail 16 preferably rests upon the bar 18 and is provided with a strap 21 secured to the rail and extending about the bar. The bar 18 may also serve as a support for other stationary retaining rails 22 extending oppositely of the rails 16 beneath the run of conveyor approaching the sprockets 1, the rails 22 being similarly provided with securing straps 23.

The upper ends of the rails 16 are carried upon a movably supported cross bar 24 by means of straps 25 secured to the rails and having yoke ends embracing the bar 24. Extending endwardly of the upper ends of the rails 16 are curved retaining rails 26 arranged concentrically to the sprockets 5 and functioning to retain the bottles in the pockets as the latter are swung about the axis of the sprockets 5 in the change of direction of the movement of the conveyor. The rails 26 are provided with yoke shaped lower ends removably embracing and supported upon the bar 24, the upper ends being also yoke shaped and embracing for support another movably supported cross bar 27, the upper yoke ends

being removably secured against displacement from the bar 27 by cross pins 28.

The cross bars 24 and 27 are endwardly supported upon the respective arms of a pair of V shaped spiders 29 pivotally mounted upon the sprocket shaft 6 at opposite sides of the conveyor. The spider 29 maintains the bars 24 and 27, and thereby the curved rails 26 and the upper ends of the straight rails 16 in constant radial relation to the sprockets 5, in whatever adjusted position the latter are placed. Movement of the shaft 6, to take up slack in the conveyor belts, causes the spider 29 to turn on the axis of the shaft 6, and by reason of the constant relation of the bars 24 and 27 to the sprockets 5, the rails 16 and 26 are maintained in constant parallelism and concentricity to the adjacent path of the pockets 14, within the limits of adjustment provided.

In Fig. 7 is shown a modification of the retaining rail construction wherein a curved section 30 is provided as a rigid extension of the rail 16, the integral rail structure being upwardly supported only by the one cross bar 24, which latter is supported and maintained in constant radial relation to the shaft 6 by a pair of arms 31 pivotally mounted on the shaft 6 at opposite sides of the conveyor.

An automatically adjustable support against sagging of the conveyor run between the sprockets 1 and 5 is also provided in association with the supporting structure for the adjustable retaining rails. A rail 32 is provided at each side of the bottle conveyor extending parallel to the rails 16 and immediately beneath the respective conveyor belts 13 and adapted to operatively support the latter in passage between the sprockets 1 and 5. The rails 32 are endwardly supported upon the cross bars 18 and 24, being secured thereto as by means of straps 33. To retain the link belts 13 upon the rails 32, a side plate 34 is suitably secured to each rail 32 and is provided with a flange overlying the belt 13, thus providing a channelway for the passage of the belt along the supporting rail. It will be obvious that by supporting the rail 32 upon the cross bars 18 and 24, the rail will at all times be in parallel relation to the bottle retaining rails 16, thus maintaining the parallel relation of the intermediate portion of the conveyor run between the sprockets 1 and 5 against sagging of the conveyor.

I claim as my invention:

1. In a bottle washing machine having a bottle conveyor comprising a series of rows of pockets supported upon a plurality of endless belts, and having a plurality of axially aligned spaced sets of sprockets operatively supporting said belts of which one set of sprockets is adjustable in position to take up slack in said belts, the combination of a

plurality of bottle retaining rails extending from adjacent said adjustable set of sprockets to adjacent a next set of sprockets in parallel relation to the path of movement of said conveyor between said sets of sprockets, and supporting means for said rails adapted to maintain said rails in constant radial distance from said sets of sprockets respectively.

2. In a bottle washing machine having a bottle conveyor including a series of pockets and a belt for supporting said pockets, and having a pair of spaced sprockets operatively supporting said belt, one of said sprockets being adjustable in position to take up slack in said belt, the combination of a bottle retaining rail positioned adjacent said sprockets in parallel relation to the path of movement of said series of pockets between said sprockets, and means for supporting said rail in constant radial distance from said sprockets respectively.

3. In a bottle washing machine, a sprocket operable upon a fixed axis, another sprocket spaced therefrom and operable upon an adjustably movable axis, a belt operatively supported upon said sprockets and carrying a series of bottle pockets, a rail extending parallel to the path of movement of said pockets between said sprockets, said rail having pivotal support at one end upon a fixed axis adjacent said sprocket with a fixed axis, and an arm pivotally supporting the other end of said rail, said arm being pivotally supported upon a movable axis coincident with the axis of said adjustably movable sprocket.

4. In a bottle washing machine, a sprocket operable upon a fixed axis, another sprocket spaced therefrom and operable upon an adjustably movable axis, a belt operatively supported upon said sprockets and carrying a series of bottle pockets, a straight rail extending parallel to the path of movement of said pockets between said sprockets, a curved rail extending concentric to the path of movement of said pockets around said movable axis sprocket, a stationary pivotal support for one end of said straight rail adjacent said sprocket with a fixed axis, and a spider pivotally mounted on an axis coincident with the axis of said movable sprocket and having a plurality of spaced radial arms, one of said arms pivotally supporting the other end of said straight rail and one end of said curved rail, and another of said arms supporting the other end of said curved rail.

5. In a bottle washing machine, a sprocket operable upon a fixed axis, another sprocket spaced therefrom and operable upon an adjustably movable axis, a belt operatively supported upon said sprockets and carrying a series of bottle pockets, a bottle retaining rail extending parallel to the path of movement of said pockets between said sprockets, a stationary pivotal support for one end of said rail adjacent said sprocket with a fixed axis,

an arm pivotally supported on an axis coincident with the axis of said adjustably movable sprocket and extending radially therefrom into supporting connection with the other end of said rail and a rail adapted to operatively support the run of said belt between said sprockets, said last mentioned rail being supported at one end upon said stationary pivotal support and being pivotally supported at the other end by said arm in coincident axial relation with the pivotal support for the adjacent end of said retaining rail.

6. In a bottle washing machine, a sprocket operable upon a fixed axis, another sprocket spaced therefrom and operable upon an adjustably movable axis, a belt operatively supported upon said sprockets and carrying a series of bottle pockets, a rail extending parallel to and supporting said belt between said sprockets, a stationary pivotal support for one end of said rail adjacent said sprocket with a fixed axis, and an arm pivotally supported on an axis coincident with the axis of said adjustably movable sprocket and extending radially therefrom into supporting relation with the other end of said rail.

7. In a bottle washing machine, a pair of spaced shafts, one of said shafts being movably supported to vary the distance between said shafts, wheels on said shafts respectively, a conveyor operatively supported upon said wheels, a rail positioned parallel to the path of movement of said conveyor, a spider pivotally mounted on said movable shaft and having a radial arm supporting the adjacent end portion of said rail, and a pivotal support for the other end portion of said rail adjacent the other of said shafts.

In witness whereof I have hereunto attached my signature.

IRVING R. HIPPENMEYER.
